UNITED STATES PATENT OFFICE

CHARLES BURTON WOODBURY, OF WASHINGTON, DISTRICT OF COLUMBIA.

BICYCLE-LOCK.

SPECIFICATION forming part of Letters Patent No. 569,594, dated October 13, 1896.

Application filed February 11, 1896. Serial No. 578,892. (No model.)

To all whom it may concern:
Be it known that I, CHARLES BURTON WOODBURY, a citizen of the United States, residing at Washington, District of Columbia, have invented certain new and useful Improvements in Bicycle-Locks; and I do hereby declare the following to be a full, clear, and exact description of the invention, such as will enable others skilled in the art to which it appertains to make and use the same.

This invention consists in the construction and arrangement of parts to form an improved locking-bicycle in which the lock may be readily removed for repair or exchange, substantially as set forth hereinafter and as illustrated in the accompanying drawings, in which—

Figure 1 is a cross-section of part of the bicycle-frame and locking parts. Fig. 2 is a cross-section of parts shown in Fig. 1, taken on a plane at right angles thereto. Figs. 3, 4, 5, and 6 show the locking parts in different positions and relations. Fig. 7 shows the two keys of the lock. Fig. 8 shows the end of one of the frame-tubes with notch for engaging with the lock. Fig. 9 shows spring used in the lock. Fig. 10 shows part of the bicycle-frame with key-inlet and reinforce-collar.

The bicycle is made in any suitable style, with a tubular frame A, in which the frame-tubes form a junction upon a cross-tubular part arranged to hold the pedal-shaft B. This shaft bears around it a series of projecting cogs C, inclosed within such pedal-shaft tube so they cannot be seen or reached from the outside, and the branch tube D is located opposite these cogs and contains the lock arranged to engage them.

The lock E is made with an inclosing eas-
ing arranged to fit inside of tube D and so that it may be inserted freely, when the pedal-shaft B is not in place, by putting it in through the pedal-shaft tube and pushing it up into tube D.

The lock-frame fits on the inside of tube D by its edges F and by arms F' at right angles to the plane of the lock, so as to be held securely in place, and has a shoulder-point F" projecting to fit in a notch d in the end of tube D, so as to bring the lock into the right position to match with the several fittings.

The lock when inserted home in tube D is

arranged to be secured in place by a barrel or key-holding pivot G inserted from the outside of tube D through a hole matching with the holes in the lock, and this barrel or key-holding pivot has a channel cut around it arranged so that when pushed in a spring part I on the lock will fall into this channel and lock it in so it cannot be removed.

The lock has a lock-bar L, which is mounted on a pivot P so as to turn as a lever, as indicated by dotted lines in Figs. 2 and 3, to lock and unlock the bicycle by engaging with or passing between the cog-teeth C of shaft B, so as to prevent the shaft from turning, or by moving out from between them to release the shaft, so the bicycle will be free for use. The lever L is held in one or the other position by projections L' on its sides, which fit against projections M' on tumbler-pieces M, mounted on the pivot P on each side of lever L. There may be any suitable number of these tumbler-pieces M, that may be desired, one on each side or more. The tumbler-pieces M are mounted in the lock-shell so as to move freely in guides in it lengthwise and have slots to fit over pivots P to admit being raised to allow the lock-bar L to be turned to lock or unlock, and then moved down with parts M' on one side or the other of parts L' to hold the bar in place.

The tumbler-pieces M are held down by springs S above and have oval keyholes arranged so that when the proper key is inserted and turned they will be raised against the springs S, so as to lift points M' off of points L' on the lock-bar L to let it turn.

The tumbler-pieces M have their keyholes oval, more or less, so the key will lift them by turning, so as to free the lock-bar L, which by the same motion will be moved into or out of engagement with cogs C of the pedal-shaft or other part to lock or unlock the bicycle, and so that by turning the key farther the tumbler will be brought into engagement again by positive motion, so as to hold the lock-bar in position either locked or unlocked, as desired, leaving the springs S only to maintain the engagement so made without chance action.

The lock-bar L has a round keyhole and a notch on one side therein arranged so the key will engage with it to turn it at the time

when all the tumblers M are released from it and so the bar may be turned freely one way or the other to lock or unlock the bicycle.

The lock has two keys K K', arranged so one, 5 K, can be used to unlock or lock the bicycle in use, as desired, and the other, K', to be used only when it is desired to lift the spring part I from the channel in holder-pivot G, so as to free it to allow it being taken out to release the lock when it is desired to take it out for repair or exchange, as when a change of lock is desired. The tube D is reinforced at the keyhole by collar H when desired to make it stronger.

15 Various modifications may be made. I claim—

1. In a bicycle a pedal-shaft having within an inclosure cogs projecting radially beyond the periphery of the shaft to its several sides, in combination with an inclosed lock-bar pivoted so its free end may move back and forth lengthwise of such shaft by means of a key, so as to pass into or out of engagement with such cogs, to lock and unlock the bicycle, substantially as set forth.

2. In a bicycle the pedal-shaft having cogs C projecting around it, in combination with a lock having a lever L held by a pivot P so as to turn to pass lengthwise of the shaft between the cogs, and a slide M' adapted to be moved by the same key as the lever to lock the lever in position locked or unlocked.

3. In a bicycle having on its pedal-shaft a cog-wheel C, a lock having the lever L pivoted to move in line lengthwise between such cogs to lock and unlock the bicycle by means of such cogs, substantially as set forth.

4. In a bicycle having on its pedal-shaft a cog-wheel C, a lock having a lever L pivoted to turn to lock and unlock the bicycle by means of such cogs, in combination with a slide adapted to be moved by a key and held

by a spring S, and having a catch M' adapted to hold the lever locked or unlocked, substantially as set forth.

5. In a bicycle a lock inclosed in a part of its frame and adapted to lock the bicycle, and having in addition to the parts adapted to lock the bicycle, a spring-holder I adapted to catch and lock the barrel G in place, and thus 5c lock the lock in its seat, and adapted to be operated by a separate key from that adapted to operate the lock, so as to enable the barrel to be removed to unfasten the lock in its seat for removal.

6. In a bicycle a tubular frame having its pedal-shaft seat arranged to form a passage-way into a seat in an upward tube of the frame, in combination with a removable lock adapted to lock the pedal-shaft, and to be inserted and removed by such passage-way and to be held in such seat, and having a projecting shoulder or part adapted to serve in connection with a notch or seat for such projection, as a guide in inserting and adjusting the lock in place properly, and in holding it secure.

7. In a bicycle a removable lock located in an inclosed seat, and having a key-barrel arranged to be inserted as a holder and having a spring-holder in the lock adapted to engage with a recess in such barrel-holder after its insertion so as to lock the holder in its seat, in combination with a special key different from a key adapted to lock and unlock the 75 lock, adapted to disengage such spring-holder and thus allow the lock to be removed.

In testimony whereof I affix my signature in presence of two witnesses.

CHARLES BURTON WOODBURY.
